UNITED STATES PATENT OFFICE.

MARION G. SLAWSON, OF GIRARD, KANSAS.

GRAIN-SHOCKER.

1,282,308.

Specification of Letters Patent. Patented Oct. 22, 1918.

Application filed July 26, 1917. Serial No. 182,850.

To all whom it may concern:

Be it known that I, MARION G. SLAWSON, a citizen of the United States of America, residing at Girard, in the county of Crawford and State of Kansas, have invented 5 certain new and useful Improvements in Grain-Shockers, of which the following is a specification.

This invention relates to grain shockers 10 of the type shown in Patent 985,750 issued to me on February 28th, 1911 and in Patent No. 1,198,285 issued to me on September 12th, 1916 and the primary object of the invention is to provide an improved feeding 15 means for delivering the bundles of grain to the shock forming arms of the aforesaid patents.

In the above named patents the bundles of grain fall from a grain binder and are 20 carried through a passage-way by endless chains having suitable means thereon for engaging the bundles of grain. In Patent No. 1,198,285 packers are employed for thrusting the bundles into the shock forming 25 arms.

According to the present invention these packers and chains are completely done away with and I mount within the passage-way a reciprocatory plunger head and I provide 30 novel, simple and highly efficient means for controlling the movement of this plunger head so that it will be released by a falling bundle of grain, will then deliver said bundle of grain firmly and positively 35 to the shock being formed and will then automatically return to a position of rest at the front end of the passageway where it will remain until it is again set in operation by the fall of another bundle of grain.

Further objects of the invention are to 40 provide improved means for holding the bundles of grain in an upright position until they are engaged by the plunger head, to provide a simple and efficient mounting 45 for the plunger head and for actuating the same, together with an improved controlling means for the several parts. A further object of the invention is to provide improved means for placing the bundles of 50 grain in the shock forming arms, said means being arranged to thrust alternate bundles upon the opposite sides of the longitudinal center of the machine so that the formed shock is symmetrical and compact.

Further objects and advantages of the in-

vention will be set forth in the detailed description which now follows:

In the accompanying drawings,

Figure 1 is a plan view illustrating a grain shaker having the invention applied thereto.

Fig. 2 is a perspective view of the plunger head actuating and controlling mechanism.

Fig. 3 is a longitudinal, sectional view through a passageway hereinafter described 65 illustrating the chain which drives the plunger head.

Fig. 4 is a rear elevation of the plunger head with the track way in section.

Fig. 5 is a detail plan view illustrating a 70 retaining arm and associated parts herein-after described.

Fig. 6 is a side view of a clutch actuating dog hereinafter described.

Fig. 7 is a detail perspective view of a 75 special link employed in the drive chain of the plunger head.

Fig. 8 is a plan view, with certain of the parts omitted, illustrating a modified form 80 of the device in which a placing mechanism for the bundles is employed.

Fig. 9 is an enlarged plan view illustrating a part of the placing mechanism upon an enlarged scale.

Fig. 10 is a detail side view of the clutch 85 hereinafter described.

Fig. 11 is a side elevation of an actuating latch for said clutch, and

Fig. 12 is a detail view of one of the 90 placers.

Like numerals designate corresponding parts in all of the figures of the drawing.

In the drawings, 5 designates a portion of a grain binder and 6 designates the rectangular frame of the shaker. This frame 95 is connected to the grain binder by an intermediate frame 7. The frame 7 carries an arm 8 that is actuated by a spring 9 to force an idler roller 10 into engagement with a sprocket chain 11 to thereby prevent undesirable loosening of said chain. This sprocket chain passes over a sprocket wheel 12 upon a shaft 13. The shaft 13 is one of the shafts of the grain binder and motion is imparted from this shaft to the longitudinal shaft 14 of the shaker through the medium of a sprocket wheel 15. As in the 100 patents above referred to, a table 16 is arranged to have reciprocatory motion imparted thereby by sprocket chains 17. These 105

110

sprocket chains pass over sprocket wheels 18 and 19, the latter of which are mounted upon a transverse shaft 20. Shaft 20 carries a bevel gear wheel 21 which is in mesh with bevel gear wheels 22 and 23. These latter gear wheels are loose upon shaft 14. A clutch 24 is splined upon shaft 14 and is adapted to be thrown into engagement with gear wheel 22 or 23 through the medium of a lever 25. This lever is pivoted at 26 upon frame 6 and its free end engages clutch 24.

The controlling means by which the clutch 24 is shifted to control the movement of the table 16 into and out of frame 6 forms no part of the present invention and is, therefore, not described, the invention in the present case residing more particularly in improved means for feeding the bundles to the shock forming arms as will be herein-after set forth.

In carrying out the present invention I drive from the shaft 14 through chain 14^a and shaft 14^b to a bevel pinion 27 which meshes with a bevel pinion 28 upon a counter shaft 29. This counter shaft carries a sprocket wheel 30 which drives by means of a chain 31 to a sprocket wheel 32 on a counter shaft 33. A clutch collar 34 is splined upon the shaft 33 and carries teeth 35 that are adapted to engage corresponding teeth 36 of a clutch member 37. The clutch member 37 is carried by a sleeve 38 which carries a sprocket wheel 39. A spring 34' normally tends to thrust the clutch collar 34 toward the clutch member 37 and when these two members are engaged with each other motion is imparted to the sprocket wheel 39 from the shaft 33. A sprocket chain 40 passes over the sprocket wheel 39 and over a sprocket wheel 41 that is disposed in a recess 42 formed in the bottom of the passageway 43. The sprocket chain 40 carries a special link 44 having an eye 45 adapted to receive the angular end 46 of a connecting rod 47. The opposite end of this connecting rod is engaged at 48 with a box 49 carried by a plunger head 50. This plunger head 50 comprises a pair of L-shaped angles 51 spaced from each other and tied together by a sheet iron face 52. This plunger head is mounted upon wheels or rollers 53 and it is suitably braced by braces 54. The wheels 55 travel in ways 55 formed in the opposite sides of the passageway near the bottom thereof. It will be apparent that movement of the sprocket chain 40 will impart longitudinal reciprocation to the plunger head 50 and thereby force through the passageway 43 any bundle of grain which may be therein. 56 designates the shock forming arms which receive the bundles of grain as they are thrust from the passageway 43 by the plunger head, these shock forming arms

corresponding to the shock forming arms in the patents aforesaid.

By referring to Figs. 2 and 3 it will be seen that the ways 55 are inclined sharply downward at the front end of the passageway so that the plunger head will, when in a position of rest, have its front face disposed at quite an angle to the vertical. This provides for room for the bundles to fall into the passageway without necessitating a corresponding increase in the length of the passageway. The downward inclination of the way is indicated at 55^a. These ways are also downwardly inclined at the rear end of the passageway as indicated at 55^b so that in the final part of the operative movement of the plunger head the upper end thereof is rocked forward to impart a final thrust to the top of the bundle into the shock forming arms 56.

The clutch collar 34 is engaged by a head 57 formed upon a lever 58 that is pivoted at 59. This lever has a curved end 60 disposed in the path of movement of a dog 61. This dog is pivoted at 62 to a sliding bar 63. The bar 63 is mounted for slidable movement by having reduced end portions 64 thereof, disposed in bearing blocks 65 and 66. A spring 67 is disposed between the bearing block 65 and a shoulder 68 of the bar 63. The dog 61 is connected by a link 69 with an arm of a bell crank lever 70, said bell crank lever being pivoted at 71 to a bearing stud 72 that is carried by the bar 63. The other arm of the bell crank lever is connected by a link 74 with an arm of a second bell crank lever 75. This second bell crank lever is pivoted at 76 and is connected by a link 77 with the tail 78 of a finger 79. The finger 79 is pivoted at 80 and when this finger lies in a horizontal plane it lies in the path of movement of the falling bundles of grain. The depression of the free end of this finger by the weight of a falling bundle of grain draws upwardly upon link 77 and imparts a pull to link 74. This in turn elevates the dog 61 through the connections described and releases the lever 60. Thereupon the spring 34' shifts the clutch collar 34 to bring the teeth 35 into engagement with the teeth 36 of the clutch member 37 and movement is imparted to the chain 40 and through the connections described to the plunger head. The plunger head travels all the way through the passageway 43 forcing a bundle of grain ahead of it and thrusts the bundle of grain into the shock forming arms as herein-after set forth. When the link 44 passes from the upper flight of the chain to the lower flight thereof the movement of the plunger head is reversed and it travels toward the front of the passageway 43. During the return movement of the plunger head it strikes a horizontally disposed lever 81. This lever is pivoted at 82

to a part of the frame and has a slightly loose connection with the bar 63 through a pin 83 and slot 84. The resultant movement of the lever 81 toward the front end of the passage causes the dog 61 to thrust against the lever 60 and rock said lever upon its pivot 69 to thereby throw the clutch collar 34 in such direction as to disengage the teeth 35 from the teeth 36 and bring the 10 plunger to a position of rest at the front end of the passage where it remains until another bundle of grain drops and strikes the finger 79. The movement of the bar 63 under the action of the lever 81 results in 15 compressing the spring 67. The bar 63 normally tends to move toward the rear end of the passage 43 but is restrained by the plunger head as long as the plunger head is in a position of rest. However, when by the 20 lifting of the dog 61 the lever 60 is free and the clutch collar 34 sets the plunger head in operation the spring 67 causes the bar 63 to follow the plunger head as it starts upon its opposite stroke and this endwise movement 25 of the bar 63 results in bringing the dog 61 to a position where it can again snap behind the lever 60 preparatory to thrusting against said lever when the plunger head again comes to the front end of the passage- 30 way. A flat spring 61' normally tends to depress the dog 61 and causes the dog to snap behind the lever 60 in the manner aforesaid.

It is to be noted that the bell crank lever 35 70 is capable of two movements. That is, it rocks upon its pivot 71 and it is subjected to a bodily movement with the bar 63 upon which it is mounted. This bodily movement of the bell crank 70 is utilized to throw the 40 finger 79 out of the path of the plunger head as follows: When the bar 63 moves under the influence of the spring 67 a bodily movement is imparted to the bell crank 70 and this bell crank thrusts through the 45 links 74 with the result that an upward movement is imparted to the links 77 whereby the tail 78 of the finger is thrust upwardly and the free end of this finger is thrown downwardly into a vertical position, 50 in which position it remains until the plunger head upon its return stroke passes the finger and contacts with the lever 81 whereupon the bar 63 is thrust in the opposite direction or against the tension of the springs 55 67 and this, through the connection described, results in swinging the finger 79 to a horizontal position where it lies in the path of movement of the falling bundles of grain as hereinbefore set forth.

60 For holding the bundles of grain in an upright position until they are properly engaged by the plunger head a retaining arm 85 is mounted upon a vertical shaft 86. The shaft 86 carries ears 87 and 88. A rod 89 65 is pivoted at 90 to the ear 88 and slides

through an upturned portion 91 of a bracket 92. A spring 93 bears between this upturned portion 91 and a part of the rod 89 and acts to hold the retaining arm 85 either in a position where it lies across the passageway 43 70 or in a position where it lies parallel with said passageway 43. In other words, when the pivot point 90 passes over the "center" the spring 93 will act to hold the arms 85 in one or the other of these positions. The ear 75 87 is connected by a rod 94 with a finger 95 that is pivoted at 96 to a bearing bracket 97 and the connections are such that when the retaining element 85 lies across the passageway the finger 95 lies out of the path of movement of the plunger head and when the retaining arm 85 lies parallel with the passageway the finger 95 lies across the passageway. 80

The result of the foregoing arrangement 85 of parts is that when the plunger head is in a position of rest the finger 95 lies out of the path of movement of the plunger head and the retaining arm 85 lies across the path of movement of the plunger head and 90 serves to hold the bundles of grain in an upright position until the plunger head in its forward travel properly engages them. Continued movement of the plunger head results in swinging the retaining arm 85 95 to a position where it is parallel with the passageway 43 so that the plunger head may pass by. This movement of the retaining arm brings the finger 95 into such position that the plunger head upon its return stroke 100 will strike the finger and in moving this finger out of the passageway will bring the retaining arm 85 back into its bundle retaining position. Spring actuated shields 98 are pivoted to the side walls of the passage 43 105 and are provided with right angular ends 100. Springs 101 bear between the side walls of the passageway indicated at 102 and 103 and the rear faces of the shields and normally tend to press these shields toward 110 each other to thereby provide a constricted mouth 104 at the rear ends of the shields. The right angular ends 100 of the shields act to pack the bundles in the shock forming arms and to prevent the bundles from 115 backing into the passageway 43.

In Figs. 8 to 12 I have illustrated an improved form of the invention wherein placers for the bundles of grain are employed. In this form of the device shaft 14 120 is connected by beveled gears 105 and 106 with a transverse shaft 107. This shaft drives, by beveled gear wheels 108 and 109, the vertical shafts 110 and 111. Fixed upon the upper ends are clutch disks 112 and 125 loosely mounted with respect to these shafts are clutch disks 113. The last named clutch disks are provided with teeth 114 that contact with notches 115 formed in arms 116 that are fixed to the frame. The disks 113 130

are provided with crank arms 117 and these crank arms are pivotally connected by links 118 with rods 119. These rods at one end are slidably mounted in blocks 120 and these blocks in turn are pivoted to bracket 121.

The rods 119 at their opposite ends are pivoted at 122 to the placers. One of these placers is illustrated in Fig. 12 and by referring to that figure it will be seen that

10 they comprise substantially U-shaped frames 123, the ends of which are connected by vertical bars 124 that are provided with teeth 125. These placers slide in bearings 126 and 127 by which they are caused to operate 15 in a straight line and obliquely across the passage 43 and within the mouth presented by the shock forming arms 56.

The object sought is to cause one of the placers to be actuated each time a bundle 20 is forced into the shock forming arms and to cause the placers to be alternately actuated so that one bundle will be thrust to one side of the central line of the passageway and the next bundle will be thrust to the 25 opposite side thereof and so on. To accomplish this I mount vertical shafts 128 and 129 upon opposite sides of the passageway 43 and these shafts carry crank arms 130 and 131 that are connected by a rod 132 that 30 extends beneath the passageway 43. The vertical shafts 128 and 129 are furthermore provided with laterally extending arms 133 that have pivotal connection with rods 134, the latter sliding through vertical exten- 35 sions 135 and being provided with springs 136, the whole constituting a "past center holding means" of a well-known type, by which the shafts 128 and 129 will be held at one of their limits of movement or the other.

40 The shafts 128 and 129 are further provided with two-part levers 137 and 138. Since these levers are alike in construction a description of one will serve as a description of both. The inner portions of these levers 45 are secured to the shafts 128 and 129 and the outer portions of the levers are pivoted to the inner portions thereof as at 139 (see Fig. 9). The abutting portions of the parts of the levers are so shaped as to constitute 50 shoulders 140 so that these levers will bend or fold in one direction but not in the other direction. The inner portions of the levers are pivotally connected at 141 to rods 142 and the opposite ends of these rods have 55 slidably mounting in frame members 143.

The rods 142 are provided with enlarged portions 142' that are slotted for the reception of dogs 144. Flat springs 145 tend to elevate these dogs and to maintain them 60 in such position that when the rods 142 are drawn forwardly these dogs will engage the cranks 117 and impart initial movement to the corresponding lower clutch disk 113. This causes the corresponding tooth 114 to 65 ride up the inclined surface 116' of recess 115

and bring the teeth 113' of the lower clutch disk into engagement with the teeth 112' of the upper clutch disk 112. Since this upper clutch disk continuously rotates it follows that a complete revolution will be 70 given to the crank 117, which revolution will only cease when the tooth 114 again reaches a position to snap into the recess 115 under the influence of a spring 146.

The inner and outer portions of the levers 75 137 and 138 are connected by springs 147 while the outer portions of these levers are connected by springs 148 with the frame at 149. The springs 148 are of stronger tension than the springs 147. With the parts in 80 the position illustrated in Fig. 1 and assuming that the plunger 50 is moved to thrust a bundle of grain into the shock forming arms, the outer portion of lever 137 will yield under the action of spring 148 to permit the plunger head to pass without affecting the placing mechanism. The plunger head 50 can pass lever 138 because the outer end of this lever has been folded over as shown in Fig. 8. After the bundle has 85 been forced into the shock forming arms and the plunger head 50 starts upon its return movement it contacts with lever 137 and moves said lever rearwardly thereby pulling upon rod 142 and through dog 144 90 imparting an initial movement to the lower half 117 of the corresponding clutch to thereby cause the inward projection of the corresponding placer. In this rearward movement of lever 137 the tension is taken 95 off the spring 148 to such an extent that spring 147 becomes stronger than spring 148 and folds lever 137 to the dotted line position shown in Fig. 9. In other words, this lever then occupies a position corresponding to that formerly occupied by lever 100 138. The rearward movement of lever 137 also results in pulling upon link 132 and swinging lever 138 toward the shock forming arms. This puts the corresponding 105 spring 148 of lever 138 under such tension as to overcome the spring 147 of said lever and straighten said lever to cause it to occupy a corresponding position to that formerly held by lever 137. Consequently, when 110 the plunger head again moves toward the shock forming arms it will entirely clear lever 137 while the lever 138 will yield to let it pass. Upon the return movement of the plunger head it will be lever 138 that 115 will be engaged and moved and the other clutch will be set in operation and the other placer will be actuated.

It has been heretofore stated that the present invention resides particularly in the 120 plunger head and the controlling and actuating means therefor. However, it is to be understood that the invention is not limited to the precise construction set forth but that upon the contrary the structure illus- 125 130

trated in the accompanying drawings is intended to be merely exemplary. The inventive thought is susceptible of being embodied in many different mechanical forms and it is, therefore, to be understood that the invention resides not only in the particular embodiment shown but that it includes within its purview whatever changes fairly come within the spirit of the appended 10 claims.

Having described my invention what I claim is:

1. In a grain shocker, the combination with a passageway adapted to receive bundles of grain, of an endless chain traveling therein, a track way, a reciprocatory plunger head mounted to travel upon the track way and a connection between the plunger head and the chain, said track way being directed 20 downwardly at each of its ends.

2. In a grain shocker, a passageway adapted to receive bundles of grain, an endless chain movable in the passageway, a wheeled plunger head mounted to travel in the passageway and an actuating rod connected to the plunger head and to the chain.

3. In a grain shocker, a passageway adapted to receive bundles of grain, a retaining arm mounted to swing from a position transverse to said passage to a position parallel with the passage and means for holding said retaining arm in either of said positions comprising a lateral extension upon the arm, a rod connected thereto, a fixed element 35 through which the rod slides and a spring bearing between the fixed element and the lateral extension.

4. In a grain shocker, a passageway adapted to receive bundles of grain, a retaining arm, a vertical shaft upon which the arm is mounted, a pair of ears carried by said shaft, spring means connected to one of said ears for holding the retaining arm in a position transverse to the passageway or in a 45 position longitudinal with respect to the passageway, a connecting rod connected to the other of said ears and a pivoted finger to which said rod is connected, the relation of the parts being such that when the retaining arm lies parallel with the passageway the finger projects into the passageway and vice versa.

5. A device of the character described comprising a reciprocatory plunger head, 55 an actuating mechanism for the plunger head, a controlling member for the actuating mechanism which, when the plunger head lies at its forward limit of travel, projects into the path of the plunger head and in a 60 position to be engaged by a falling bundle of grain to thereby set the plunger head in operation and means operable upon the initial movement of the plunger head to swing the controlling member out of the path of 65 movement of the plunger head.

6. In a device of the character described, the combination with a reciprocatory plunger head, of an actuating mechanism for the same including a clutch, a driven element which is periodically connected to the actuating mechanism by said clutch, means normally tending to move the clutch to engaging position, a lever which when moved in one direction holds the clutch out of action, a longitudinally movable bar, spring means 70 for actuating said bar in one direction, a restraining member pivoted upon said bar, a pivoted controlling element for the restraining element and connections between the controlling element and the restraining element which are so arranged that movement of the controlling element upon its pivot under the influence of a falling bundle of grain will rock the restraining element upon its pivot to release the lever and permit the 75 clutch to be set in operation while endwise movement of the longitudinally movable bar imparts bodily movement to the restraining element to act through said connections to swing the controlling element upon its pivot 80 and move it out of the path of the plunger 85 head.

7. A structure as recited in claim 6 comprising an element lying in the path of movement of the plunger head and connected to the longitudinally movable bar to shift and same and throw the clutch out of action by the engagement of the restraining means with the latter, when the plunger head reaches its forward limit of travel. 95

8. In a device of the character described, the combination with a reciprocatory plunger head, of an actuating mechanism therefor comprising a clutch, a slidable bar, spring means for moving said bar rearwardly, means connected to the bar and projecting into the path of movement of the plunger head for actuating said bar forwardly, a clutch actuating lever, spring means tending to move the clutch to 100 clutched position, a bell crank lever pivoted upon the slidable bar, a second bell crank lever, a link between an arm of the first bell crank lever and an arm of the second bell crank lever, a controlling finger pivoted intermediate its ends, a link connection between the rear end of said controlling finger and the other arm of the second bell crank lever and a restraining means for the clutch actuating mechanism connected to the first 110 named bell crank lever.

9. In a device of the character described, the combination with a passageway, of a reciprocatory plunger mounted to move therein, an endless chain traveling therein 115 to which the plunger is connected, a driven member for the chain, a continuously moving shaft, a clutch between said shaft and the driven member of the chain, spring means normally tending to move said clutch 120 named bell crank lever.

130

to closed position, a clutch controlling lever pivoted intermediate its ends, a slidable bar, a dog carried by the slidable bar for engaging the clutch controlling lever, spring means normally tending to move the slid-
 5 able bar in one direction, a bell crank lever pivoted upon the movable bar and having one of its arms connected to the dog, a bundle actuated finger and connections be-
 10 tween the bell crank lever and said finger of such nature that when a bundle contacts with said finger the bell crank lever is rocked upon its pivot to lift the dog and release the clutch controlling lever and
 15 permit the clutch to move to operative position, while bodily movement of the bell crank lever with the slidable bar acts through said connections to throw the controlling finger to a position where it lies
 20 out of the path of travel of the plunger head.

10. In a device of the character described the combination with shock forming arms, of a reciprocatory plunger for thrusting the
 25 bundles of grain thereinto and a placer set in motion by the movement of said plunger for placing the bundle of grain in proper position within the shock forming arms.

11. In a device of the character described the combination with shock forming arms, a reciprocatory plunger for thrusting the
 30 bundles of grain thereinto and a pair of alternately acting placers controlled by the movement of the plunger, one of said placers
 35 being actuated at each movement of the plunger.

12. In a device of the character described, the combination with shock forming arms, a passageway leading thereto, a reciprocatory
 40 plunger in the passageway, a pair of obliquely disposed placers, a single revolution clutch for each of the placers, and means controlled by the movement of the plunger head for setting the clutches in operation.

45 13. A structure as recited in claim 12, in which the movement of the plunger head which sets one of the clutches in operation also sets the parts in such position that the other clutch will be set in operation upon the
 50 succeeding movement of the plunger head.

14. In a grain shucker the combination with a reciprocatory plunger head, of an actuating mechanism therefor including a clutch, a continuously driven element to
 55 which the mechanism is periodically connected by the clutch, means normally tending to move the clutch to engaging position, a restraining element for holding the clutch out of engagement, a controlling member ar-
 60 ranged in the path of falling bundles of grain, connections between the controlling element and the restraining mechanism for releasing the restraining mechanism to per-
 65 mit the clutch to move to engaging position to thereby cause it to set the plunger head in

operation when a bundle of grain strikes the controlling member and means operable upon the initial movement of the plunger head to swing the controlling member out of the path of movement of the plunger head.

15. A device of the character described comprising a reciprocatory plunger head, an actuating mechanism for the plunger head, a controlling member for the actuating mechanism which, when the plunger head lies at its forward limit of travel projects into the path of the plunger head and in a position to be engaged by a falling bundle of grain, a clutch, connections between the controlling member and the clutch for setting the clutch in operation when the controlling member is struck by a falling bundle of grain and means operating through said connections for moving the controlling member out of the path of movement of the plunger head upon the initial forward movement of said plunger.

16. A device of the character described comprising spaced side walls constituting a passageway between them, a bottom for the passageway having tracks formed along its opposite sides, a traveling chain one flight of which is disposed above said bottom, a plunger head mounted to travel in the passageway, a connection between the plunger head and the chain, driving connections for the chain including a clutch, a controlling member for the clutch mounted independently of the plunger head and arranged to project into the path of movement of the falling bundles of grain and connections between said controlling member and the clutch for actuating said clutch to set the chain and plunger head in motion when the controlling member is struck by a falling bundle of grain.

17. A structure as recited in claim 16 wherein means are provided acting through said connections for swinging the controlling member out of the path of movement of the plunger head upon initial movement of said plunger head.

18. A device of the character described comprising side walls constituting a passageway between them, a bottom for said passageway having channeled edges constituting track ways said bottom and track ways being tilted downwardly at the opposite ends thereof, a wheeled plunger head the wheels of which are mounted in said track ways, an endless chain one flight of which is disposed to travel above said bottom, a connection between the plunger head and said flight of chain, driving connections for the chain including a clutch and means controlled by the falling bundles of grain, for actuating said clutch.

19. In a device of the character described, the combination with shock forming arms,

a passageway leading thereto, a reciprocatory plunger in the passageway, a pair of placers, one upon each side of the passageway and movable obliquely with respect thereto, a pair of foldable levers, means controlled by the movement of said levers under the influence of the plunger for setting the placers in motion and for causing them to make one complete movement into 10 and out of the shock forming arms, interconnecting means between the foldable levers and means for causing one of said le-

vers to assume a folded position when the other is projected into the passageway and vice versa.

20. A structure as recited in claim 19 in which the last named means comprises a pair of springs for each foldable lever, one of said springs connecting the two parts of the levers and the other of said springs connecting the outer part of the lever to a fixed point.

In testimony whereof I affix my signature.
MARION G. SLAWSON.
